UNITED STATES PATENT OFFICE.

SIMONE RENNA, OF BROOKLYN, AND LEUIGI RENNA, OF NEW YORK, N. Y.

FAN ATTACHMENT FOR SEWING MACHINES.

Application filed December 27, 1926. Serial No. 157,191.

The present invention relates to improvements in sewing machine attachments, and has for an object to provide a fan and supporting and driving means, whereby the movement of the fan may be occasioned by the driving mechanism of the sewing machine, and whereby further the momentary stopping of the sewing machine or the impulsive operation thereof may not interfere with the continuous movement of the fan element.

Another object of the invention is to provide a fan attachment for sewing machines, in which the fan element is mounted for adjustment to direct the air in any desired vertical or horizontal line toward or away from the operator of the machine.

A further object of the invention resides in providing a fan attachment of simple, compact and inexpensive form, and which is susceptible of being attached to the machine without requiring any alteration therein.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a fragmentary front elevation of a sewing machine with the improved fan attachment;

Figure 2 is an end view thereof;

Figure 3 is a fragmentary rear view of the same;

Figure 4 is a fragmentary vertical section taken on an enlarged scale through the fan shaft and its supporting means;

Figure 5 is a vertical section taken on the line 5-5 in Figure 4;

Figure 6 is a similar section taken on the line 6-6 also in Fig. 4;

Figure 7 is a section taken on the line 7-7 in Figure 2; and

Figure 8 is a cross-section taken on the line 8-8 in Figure 7.

Referring more particularly to the drawings, 10 designates the table and 11 the metal framework of a usual form of sewing machine having the belt pulley wheel 12 driven by the belt connection 13 either through a treadle or by other appropriate motive power.

55 In accordance with the present invention, the drive belt 13 is utilized to drive the fan

element, and for this purpose a grooved wheel 14 is provided to engage with one run of the belt 13, preferably the rear flight thereof, and this grooved pulley is, as shown in Fig. 7, fixed upon a shaft 15 journalled through a hollow externally threaded bearing sleeve 16. This bearing sleeve is of generally cylindrical form in cross-section, as shown in Fig. 8, except that its top portion is flattened, as indicated at 17, to receive the upper flattened portion 18 of the bracket arm 19 having an opening 20 to freely receive said bearing sleeve 16. The bearing sleeve 16 is held in place against external movement on the bracket arm 19 by means of the post nuts 21 and 22. By running one of these nuts off the sleeve, the bracket arm and bearing sleeve may be separated.

The bracket arm 19 is shown as extending down and adjustable horizontally through the slot 23 and set screw 24, the support for the bracket arm being had from the vertical web 25 of a main bracket, provided with the horizontally elongated slots 26 shown in Fig. 2, to receive the post or set screw 27 projecting out from the sewing machine standard.

The web 25 of the main bracket is provided with a horizontal web portion 28 for sustaining at its inner free end the post 29, which carries the fan, this post being provided with the collar 30, having the slotted extension piece 31 for receiving the set screw and post 32 projecting out from the upper portion of the sewing machine column, whereby to steady the fan post 29. At its upper end the fan post is provided with the longitudinally perforated block 33, having the set screw for securing in adjusted position the rod 35. This rod is threaded at its upper end, to which the nuts 36 and 37 are applied, holding therebetween the intermediate portion of the fan yoke 38. As shown in Fig. 5, the fan yoke is provided with the trunnions 39 and 40, which engage at diametrically opposite points the spherical block 41. Through this block and extending at substantially right angles to the axes of the trunnions 39 and 40, but in substantially the same plane therewith is a bearing sleeve 42 having its ends 43 and 44 flanged. The bearing sleeve is adapted to receive the fan shaft 45, which projects beyond both ends of the spherical block, carrying at one end the grooved pul-

105
110

ley 46, engaged by the yieldable, resilient or stretchable belt 47 driven by the grooved wheel 48 carried upon the shaft 15 and driven from the grooved wheel 14, which engages the drive belt 13 of the machine.

The grooved wheel 46 engages at one side against the enlarged flange 44 of the bearing sleeve 42 and at its opposite side against the nut 49 threaded upon the projecting 10 end of the fan shaft 45. The opposite smaller flange 43 of the bearing sleeve is countersunk in the spherical block 41 and relieves the block of the wear of the fan cage 50. This fan cage is shown as composed of four arms spaced at 90° and having their free ends bent outwardly and carrying therein the wire guard 51 at the front of the fan, the blades of which are designated at 52. These blades are carried 15 by a hub 53, which is loosely mounted on the fan shaft 45 and is provided with the inclined or ratchet teeth 54, as shown in Fig. 6. The hub and ratchet teeth are contained 20 within a casing 55, to which is secured, as indicated at 56, a long volute spring 57, 25 enveloping the ratchet teeth 54 completely and having its free inner end disposed to engage against the abrupt shoulders of the teeth for driving the teeth and incidentally 30 the fan hub and blades in a counter-clockwise direction, as viewed in Figure 6.

The casing 55 is composed of the outer circumferential rim 55 and the right angular disc 58, which is affixed as by the nuts 59 35 and 60 to the adjacent threaded end of the fan shaft 45.

The spherical block 41 is provided on its end portion with an arcuate rack 61 engaged by a dog 62 having an arcuate tooth 40 engaging edge 63 extending at right angles to the direction of the arc of the rack 61 and having its convex side disposed toward said rack, whereby the dog may be 45 swung out of engagement with the teeth of the rack to permit the spherical block 41 to be adjusted about the horizontal trunnions 39 and 40. The fulcrum or pivot 64 of the dog is shown as being carried by an upturned ear 65 extending laterally from 50 the intermediate portion of the yoke 38.

In the use of the device, the movement of the drive belt 13, as by the depressing of the treadle of the sewing machine, will operate to rotate the grooved wheel 14 in contact therewith. A like rotary movement is communicated to the shaft 15 and pulley 48 thereon. The belt 47 is thereby driven, driving in turn the pulley 46, fan shaft 45, casing 55, spring pawl 57 and the ratchet 55 hub and fan blades. Should the sewing machine be momentarily stopped for any reason, the fan blades 52 and hub carrying same will continue to rotate in the counter-clockwise direction indicated by the arrow 60 in Fig. 6, the inclined sides of the teeth 65

simply slipping over the free end of the volute pawl spring 57 and racing ahead of the housing 55. The same result will be had when the sewing machine is operated fitfully. The fan will not thereby stopped 70 and started impulsively, but it will be permitted to rotate more or less continuously, its continuous movement being had by the momentum previously acquired.

Various adjustments are made possible 75 by the slot 26 in the main bracket, enabling the fan to be adjusted toward or from the operator. It may also be raised and lowered by adjusting the set screw 34 and the elastic belt 47 will take up any slack that would otherwise occur in an inextensible belt. Moreover, the fan may be directed up or 80 down by first disengaging the dog 62 and then swinging the spherical block 41 on the horizontal trunnions 39 and 40 of the yoke. The tailpiece or handle 66 of the dog will 85 possess sufficient weight to swing the dog back into engagement with the teeth 61 merely upon release of the operator.

The groove in the pulley 46 will be sufficiently deep to hold the belt against escaping when this last mentioned adjustment is made, as provision is also made for supplying lubricant to the various parts.

It will be obvious that many changes in 95 the construction, combination and arrangement of parts could be made, which could be used without departing from the spirit of our invention, and we do not mean to limit the invention to such details, except as particularly pointed out in the claims.

Having thus described our invention, what we claim and desire to secure by Letters Patent of the United States is:

1. In combination with a belt driven machine, a fan, and means driven by said belt driven machine for communicating movement to the fan and for causing the fan to run free of said means and by its own momentum on slowing or stopping of the machine.

2. In combination with a sewing machine having a belt drive, a fan, means for driving the fan from movement derived from said belt, and means for causing the fan to run free ahead of said drive means when the belt is slowed or stopped.

3. In combination with a belt driven machine, a fan, a ratchet mechanism for driving said fan in one direction and causing the fan to run free when the ratchet mechanism is slowed or stopped, and connections between said ratchet mechanism and the belt for driving the former.

4. In a combination with a belt driven machine, a support thereon, a bearing swivelly carried by said support, a fan shaft carried by said bearing member, means for driving said shaft by movement derived from the belt, a fan coupled to be driven

by said shaft when rotated in one direction, and means whereby the fan may run ahead of the shaft when the latter is slowed or stopped.

5. In a belt driven machine, a support, a bearing member carried by said support, a fan shaft journalled in said bearing member, means for driving said shaft, a housing fixed to said shaft, a fan having a hub loosely mounted over said shaft and provided with ratchet teeth in the housing, and a volute spring secured in the housing and wound about said hub with its free end engaging the ratchet teeth, said free end being biased to the center of the hub.
6. In a belt driven machine, a support, a bearing member carried thereby, a fan shaft journalled through said bearing member, means for driving said fan shaft, a fan loosely mounted about said fan shaft, cou-

pling means fixed to move with the shaft and to drive the fan in one direction, but to release the fan when stopping or slowing below the rate of speed acquired by the momentum of the fan, and means for adjusting said bearing member about a substantially horizontal axis. 25

7. In a belt driven machine, a support, a yoke adjustably carried by said support, a bearing member swivelly carried in said yoke, a fan carried by said bearing member, means for driving said fan, a rack carried by said bearing member, and a swivel weighted dog carried by said yoke for engagement with said rack. 30

In testimony that we claim the foregoing as our invention, we have signed our names hereto. 35
